US00D882960S

(12) **United States Design Patent** (10) **Patent No.:** **US D882,960 S**
Ji et al. (45) **Date of Patent:** **** May 5, 2020**

(54) **ORAL CARE IMPLEMENT**

- (71) Applicant: **Colgate-Palmolive Company**, New York, NY (US)
- (72) Inventors: **Yan Mei Ji**, YangZhou (CN); **Wen Jin Xi**, Shanghai (CN)
- (73) Assignee: **Colgate-Palmolive Company**, New York, NY (US)
- (**) Term: **15 Years**
- (21) Appl. No.: **29/680,390**
- (22) Filed: **Feb. 15, 2019**

Related U.S. Application Data

- (62) Division of application No. 29/626,368, filed on Nov. 16, 2017, now Pat. No. Des. 845,637.

(57) **CLAIM**

The ornamental design for an oral care implement, as shown and described.

DESCRIPTION

FIG. 1 is a front perspective view of an oral care implement according to a first embodiment of the new design; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a front perspective view of an oral care implement according to a second embodiment of the new design; FIG. 10 is a rear perspective view thereof; FIG. 11 is a front view thereof; FIG. 12 is a rear view thereof; FIG. 13 is a left side view thereof, FIG. 14 is a right side view thereof; FIG. 15 is a top view thereof; and, FIG. 16 is a bottom view thereof.

The broken lines in the drawings formed by linear segments of equal length illustrate portions of the article that form no part of the claimed design. The broken lines in the drawings formed by a dash-dot-dash sequence illustrate an unclaimed boundary.

1 Claim, 8 Drawing Sheets
